UNITED STATES PATENT OFFICE.

ARTHUR S. HAWKS, OF ST. LOUIS, MISSOURI, ASSIGNOR TO BUSCH-SULZER BROS.-
DIESEL ENGINE COMPANY, OF ST. LOUIS, MISSOURI, A CORPORATION OF MISSOURI.

INTERNAL-COMBUSTION ENGINE.

Application filed January 18, 1921. Serial No. 438,067.

- The invention relates to internal combustion engine valve gear of the kind that is adjustable while the engine is in motion to vary the lift or timing of a valve or to change over from one valve to another as in the case of engines which are started and initially run by the valved admission of compressed air and later by the valved admission of fuel.
- Such adjustable valve gear as heretofore designed are required to be of substantial proportions and of considerable mass and inertia, and are therefore shiftable only with difficulty when they are in motion and in large sized engines frequently require special motors for shifting them, and if made of lighter design so as to be adaptable to hand operation, have the objection that they transmit the force and shock of the cam motion to the controlling members or to the operator's hand. The purpose of this invention is to provide an adjustable valve gear that is strong and light in weight and also capable of adjustment with little effort.
- To this end the connection means by which the valve is operated by the valve shaft or cam shaft is composed of hinged links acting like a unitary member when suitably supported but which can be collapsed or distended when required to change its relation to its cam or other operating element, as later described. A further purpose is to provide a plurality of connection means so related that the actuation of a single control or rod will cause their respective valves to be brought into operation only in a predetermined sequence. The articulated connector herein disclosed is adapted to these uses and especially to the control of the valves in air started or reversible engines.
- In the accompanying single sheet of drawings I have illustrated the invention as applied to an air started engine but it will be obvious that the invention is not limited to the construction shown.
- Figure 1 is an elevation, partly in section, showing the mechanism in position for operating the starting air valve the fuel valve being out of action.
- Figure 2 diagrammatically shows the mechanism in an intermediate position in which both valves are out of action, and Figure 3 shows the fuel valve alone in operation.
- The cylinder 1 of the internal combustion
- engine (which may comprise any number of cylinders) is waterjacketed as usual at 2 and provided with a common form of valve 3 for admitting compressed air from a pipe 4 to start the engine and a valve 5 of the injection type for the liquid fuel on which the engine normally operates; the fuel valve has the usual spring 6 to close it and a bell crank lever 7 that directly operates the valve against the spring. The other cylinders may be assumed to be similarly equipped and all the cylinders may be assumed to be provided with such other valves and gears as are necessary for the operation of the engine. The usual cam shaft 8 that operates the valves of all the cylinders is so driven from the engine crank shaft (not shown) that its valve cams 9 and 10 operate the air and fuel valves respectively and as required.
- When starting the engine, the fuel valves 5 are rendered inoperative, or disconnected from their operating cams 10, while the air valves are in action. When the engine has acquired sufficient speed by air operation, the air valve connectors are displaced from the cams 9 so as to be no longer operative thereby and the connectors of the fuel valves are brought into engagement with the fuel cams 10, so as to cause fuel to be injected according to the normal engine cycle.
- The valve connector between the air valve 3 and its operating cam 9 is an articulated member comprising in this instance two links 11 and 14 hinged together at 13, the link 11 being jointed to the stem of the air valve and the other link being provided with the usual roller or cam-follower 15 which is supported by the link 17 so that it may engage the cam 9. The joint 13 is supported by a link 16 so as to keep the two links in substantial alignment or in such relation that they together act like an ordinary push rod for transmitting the cam motion to the valve and conjointly they serve to operate the valve in regularly recurring sequences in phase with the engine cycle. The air starting cam 9 pushes the connector to the left to open the valve and spring 18 closes the valve, returning the connector to the right when the nose of the cam passes beyond the roller 15. The movement of the connector to the right under the action of the valve spring is limited by the valve striking its seat while, obviously, the extent

to which the valve is opened depends upon the extent to which the connector penetrates into the range of action of the cam.

The supporting link 16 is carried by the 5 end of a crank arm 20 on a rock shaft 19 which later is adapted to be rotated by a crank arm 22 provided with a connecting rod 21 extending to the control station. The shaft 19 may be common to all the cylinders 10 of the engine and is herein termed the control shaft inasmuch as its function is to control the operation of the air and fuel valves. With such shaft held in the extreme position shown in Fig. 1 in which the connector 15 is practically straight, its cam roller 15 penetrates to its maximum depth into the range of action of the cam 9 and therefore the air valve 3 is subject to its maximum lift as the cam shaft rotates. When however, the 20 control shaft 19 is turned to the left from its position in Fig. 1, as by a downward pull on the rod 21, the joint 13 is depressed accordingly and the effective length of the connector is thereby correspondingly shortened so that the cam roller 15 is withdrawn 25 from the action of the cam to an extent corresponding to the change of angular position of the control shaft. Assuming that the control shaft movement has only partly withdrawn the cam follower the cam will 30 continue to strike the roller 15 and move the connector to the left but obviously under these circumstances imparts a less opening movement to the valve, and it will be 35 apparent that further movement of the control shaft will further diminish the action of the valve, eventually causing it to cease entirely.

According to this invention the further 40 movement of the control shaft beyond the point which disengages the air valve gear, is available for similarly controlling the fuel valve, either through the same or a different form of valve connection; for example the fuel valve bell crank 7 may be 45 operated by a simple push rod 24 pivoted to it and supported at its cam end by a swinging link 26 hung from an eccentric point of support on control shaft 19 as indicated 50 in Fig. 3 and provided with the usual cam follower 25 at this end to engage the fuel cam 10 which may be assumed to be located adjacent the air cam 9 on shaft 8. The 55 link 26 is of such length that when the air valve gear is active the roller 25 will be out of the range of the fuel cam, being below it in the present case and as shown in Figs. 1 and 2, but when the control shaft is rotated as above described it is lifted and the 60 push rod is thereby brought into the position in which it will be reciprocated by the fuel cam, to cause the injection of fuel into the engine. Desirably such reciprocation will begin to occur immediately that the 65 cam roller 15 is safely out of the range of

the air cam, and as indicated by the dotted lines in Fig. 2, but this is a matter of design and can be varied as required. Further left hand turning of the control shaft, brings the cam follower 25 further into the range 70 of its cam 10 as soon as the position of Fig. 2 is passed. The limit of the movement toward the fuel cam is shown in Fig. 3 in which the connector lies in the straight line joining the valve lever 7 and the cam shaft; 75 the maximum opening movement of the fuel valve is secured with the connector in this position. Between the limit positions of Figs. 2 and 3 the degree of opening of the fuel valve as well as its timing is obviously 80 variable according to the position of the connector. It follows that the range of operation of the fuel valve lies between Figs. 2 and 3 and the range of the air valve between Figs. 1 and 2, while Fig. 2 represents a neutral position.

The practical operation of starting the engine consists in first setting the control shaft in the position calling for full operation of the air valves and after the engine 90 is in operation on compressed air, advancing the position of the shaft to diminish and eventually cut out the action of the air valves and then to begin the injection of the fuel, one continuous motion serving for all 95 these purposes and serving also if desired as the means of regulation of the fuel injection for normal engine running. In the case of reversible engines the shift of the cam shaft or of the connectors can be effected 100 in the neutral interval represented by Fig. 2 when the cams and both valve connectors are relieved of their normal pressure. Certain features of the structure above described 105 are shown in my copending application.

Claims.

1. In a combustion engine, the combination of a valve thereof, an actuator for said valve, and a push-rod type of connector composed of links hinged to each other, one end of the assemblage of links being in operating relation to the valve and the other end in operating relation to said actuator, and means for maintaining the links in a substantially fixed relation to each other during successive actuations of the connector by said actuator.

2. In a combustion engine, the combination of a valve thereof, an actuator for said valve, and a push-rod type of connector composed of links hinged to each other, one end of such assemblage of links being in operating relation to the valve and the other end in operating relation to said actuator, and a swinging link supporting a joint of said assemblage, said swinging link being supported at a point remaining fixed in position during successive actuations of the connector by said actuator.

3. In a combustion engine, the combina-

tion of a valve thereof, a rotating cam to actuate said valve, and a connector between said valve and cam composed of two links hinged to each other, one end of said hinged structure being arranged to be thrust against by said cam and the other end being arranged to actuate the valve as the hinged structure is actuated by the cam thrust, and a swinging link to support the joint between the first mentioned links, said swinging link being supported from a point remaining in fixed position during successive actuations of the connector by the cam.

4. The combination of claim 3, characterized by the fact that the end of the hinged structure which is arranged to be thrust against by the cam, is supported by a swinging link.

5. The combination of claim 3 characterized by the fact that the end of the hinged structure adjacent the valve, is hinged to the valve.

6. The subject matter of claim 1, in combination with controlling means for changing the position of the means mentioned for maintaining the links in substantially fixed relation to each other, so as to change the relation of the links to each other and thereby change the operation of the valve by the actuator.

7. In a combustion engine, the combination of a valve thereof, a rotating cam for actuating said valve, a push-rod type of connector composed of links hinged to each other, one end of such assemblage of links being in operating relation to the valve and the other end in operating relation to said cam, a swinging link to support a joint of said assemblage, and a controller on which said swinging link is supported, said controller being arranged to hold the point of support of said swinging link fixed in position during successive actuations of the connector by said cam and to move the swinging link from one position to another at will to change the relation of the links of the assemblage to each other.

8. The combination in an internal combustion engine, of a valve, an actuating element for said valve, an articulated connector, a supporting member hinged to said connector at a joint thereof, and relatively

fixed means to which the supporting member is hinged, said means serving to hold the connector within the operating range of the valve actuating element for successive regularly recurring operations of the connector by said actuating element and being movable to move the connector into and out of the operating range of the actuating element.

9. The combination in an internal combustion engine, of valve means, an actuating element, therefor, an articulated connector hinged at one end to said valve means, the opposite end of said connector engaging said actuating element, a rotatable control shaft, a link hinged eccentrically to said shaft to support the joint of said articulated member, and a hinged link to support that end of said articulated member which engages the actuating element.

10. The combination in an internal combustion engine, of valve means, actuating elements for said valve means, an articulated connector arranged to engage one of said actuating elements, a second connector arranged to engage another of said actuating elements, and means for changing the position of the joint of said articulated connector to move the latter into and out of the operating range of its actuating element, said means simultaneously moving said second connector toward and from the operating range of its actuating element.

11. The combination in an internal combustion engine, of valve means, actuating elements for said valve means, an articulated connector of the push-rod type between said valve means and one of said actuating elements to transmit motion from the latter to the former, a second connector between said valve means and another of said actuating elements, a rotatable control shaft, and links hinged eccentric to said shaft for supporting a joint of said articulated connector and supporting the second connector so that turning the shaft simultaneously moves the articulated connector toward and the second connector from the operating range of their respective actuating element and vice versa.

In testimony whereof, I have signed this specification.

ARTHUR S. HAWKS.
